[57] CLAIM

The ornamental design for an oscillator sprinkler, substantially as shown.

DESCRIPTION

FIG. 1 is a perspective view of an oscillator sprinkler embodying our new design;

FIG. 2 is a right side elevational view thereof;

FIG. 3 is a rear elevational view thereof;

FIG. 4 is a front elevational view thereof;

FIG. 5 is a left side elevational view thereof;

FIG. 6 is a top plan view thereof;

FIG. 7 is a bottom plan view thereof;

FIG. 8 is a cross sectional view taken on the line 8—8 of FIG. 2; and

FIG. 9 is a cross sectional view taken on the line 9—9 of FIG. 2.

*Fig. 1.**Fig. 3.**Fig. 2.**Fig. 4.**Fig. 8.**Fig. 5.**Fig. 6.**Fig. 7.**Fig. 9.*
